(57) **CLAIM**

The ornamental design for window wiper for vehicle, as shown and described.

DESCRIPTION

FIG. 1 is a perspective view of window wiper for vehicle showing my new design;

FIG. 2 is a front elevational view of the window wiper for vehicle;

FIG. 3 is a rear elevational view of the window wiper for vehicle;

FIG. 4 is a left side elevational view of the window wiper for vehicle;

FIG. 5 is a right side elevational view of the window wiper for vehicle;

FIG. 6 is a plan view of the window wiper for vehicle;

FIG. 7 is a bottom view of the window wiper for vehicle;

FIG. 8 is a close-up view of the window wiper for vehicle as shown in FIG. 1;

FIG. 9 is a close-up view of the window wiper for vehicle as shown in FIG. 2;

FIG. 10 is a close-up view of the window wiper for vehicle as shown in FIG. 3;

FIG. 11 is a close-up view of the window wiper for vehicle as shown in FIG. 4;

FIG. 12 is a close-up view of the window wiper for vehicle as shown in FIG. 5; and,

FIG. 13 is a close-up view of the window wiper for vehicle as shown in FIG. 6.

The matter delineated in broken lines forms no part of the claimed ornamental design.

1 Claim, 8 Drawing Sheets
